UNITED STATES PATENT OFFICE.

LEON TKACHUK, OF ALDERGROVE, BRITISH COLUMBIA, CANADA.

DESIGN FOR A SLED.

59,388.

Specification for Design.

Patented Oct. 11, 1921.

Application filed June 1, 1921. Serial No. 474,260. Term of patent 3½ years.

To all whom it may concern:

Be it known that I, LEON TKACHUK, a citizen of Roumania, residing at Aldergrove, in the Province of British Columbia and Dominion of Canada, have invented a new, original, and ornamental Design for Sleds, of which the following is a specification, reference being had to the accompanying drawing, forming a part thereof.

The figure is a perspective view of my sled, showing my design.

I claim:

The ornamental design for a sled, substantially as shown.

LEON ^{his} X TKACHUK.
